TOY TYPEWRITER

Earl D. Boisselier, Glen Ellyn, Ill.

Application January 7, 1936, Serial No. 57,985

7 Claims. (Cl. 197—47)

This invention relates to toy typewriters of the type used both for educational purposes and amusement of juveniles.

A primary object of the invention is to provide features of construction which simplify the operation and manipulation of the impression member as well as the platen carriage feeding means, thereby enhancing the reliability and practicability of the device, while at the same time providing a more substantial construction which enables the operator to more closely simulate the work produced by standard machines.

A further object is to provide a type wheel or type unit including so-called upper and lower case characters made of metal, thereby not only insuring clear and accurate impressions on the paper by use of a ribbon, but also making it possible to make carbon copies. In that connection, it is proposed to mount the carrier for the type wheel in such a way as to provide a relatively wide clearance between the type wheel and the platen in order to more clearly observe the letters being typed.

A further object of the invention is to provide a carrier for the type wheel which is constantly impelled or moved away from the platen by spring means, thus eliminating the manual operation for effecting the return of the type wheel to normal position, and, to also provide separate keys respectively for typing small and capital letters without requiring the setting of special levers or equivalent elements to effect the typing of different letters.

A further object is to provide means for effecting a manual operation to space each letter by moving the platen step by step after a letter has been typed, and to also release the platen carriage after the completion of a line for return to normal position.

A further object is to provide a novel platen and platen carriage structure which greatly facilitates the manipulation of the paper.

With the foregoing and other objects in view, which will become more fully apparent as the nature of the invention is better understood, the same consists in the novel features of construction, combination and arrangement of parts, hereinafter more fully described, illustrated in the accompanying drawings and defined in the appended claims.

A preferred and practical embodiment of the invention is shown in the accompanying drawings, in which:—

Figure 1 is a top plan view of the improved toy construction.

Figure 2 is a front elevation.

Figure 3 is a vertical cross-sectional view taken through the type wheel and its carrier, the parts being shown in their normal at rest position.

Figure 4 is a diagrammatic vertical sectional

view similar to Figure 3 showing the relative movement and position of parts when the small type key is pressed to type small letters.

Figure 5 is a view similar to Figure 4 showing the relative position of parts when the capital letter key is pressed to type capital letters.

Figure 6 is a detail vertical sectional view showing the type wheel carrier and means for operating the same.

Figure 7 is a detail view of the platen spacing mechanism.

Figure 8 is a view of the parts shown in Figure 7 in the position wherein the platen carriage feeding means is disengaged from the carriage rack to effect release of the latter, thereby to permit shifting of the carriage or platen back to starting position.

Similar reference characters designate corresponding parts throughout the several figures of the drawings.

In the embodiment shown in the drawings, the present device includes a casing designated generally as A, having a central raised wall portion A' for supporting the ribbon rollers R in such a position that the ribbon R' may be pressed forward by the type wheel unit B toward the platen device designated generally as C. For the purpose of effecting the feeding and release of the platen device C, suitable manually controlled lever means D is provided. The latter means is located at one side of the type wheel unit B, as will be apparent from Figure 1, so that it may be manipulated by the left hand of the typist while the type wheel unit B may be operated by the fingers of the typist's right hand. To that end, the type wheel unit B is controlled by two separate keys E and F respectively for actuating the type wheel unit and effecting the printing of small letters and capital letters, as desired, by the mere act of depressing the selected key.

Referring first to the type wheel unit B, it will be pointed out that the same includes a metallic disk or wheel 1 having an upper row of small letters or characters 2 and a lower row of capital letters or characters 3. The body of the type wheel is provided with a central upstanding hollow boss 4 which affords a finger grip for aiding the operator in turning to the selected letter. The hollow boss also houses a coil spring 5 surrounding a pivot stud 6 whereby the type wheel proper is resiliently mounted on the upper arm portion 7 of a carrier 8. For the purpose of holding the type wheel in the desired set or adjusted position, the bottom edge portion thereof may be notched or serrated at the location of the various letters, thereby to receive the upper end 7a of a drag spring 7b which is clamped between the central portion of the type wheel proper and the arm 7 of the type carrier 8.

The type carrier 8 is preferably formed from

a sheet metal stamping and the side flanges 8^a thereof are preferably enlarged as indicated at 8^b and are also perforated to receive the cross pin 9. The forward end of the arm 7 of the type carrier 8 is tensioned by spring 10 whose upper end engages with the arm while the lower end is anchored as indicated at 10^a (Figure 3).

The cross pin 9 in the carrier 8 has the opposite end portions thereof pivotally and shiftably mounted for vertical movement in the slots 11 in the opposite parallel bracket plates 12-12 provided within the casing (Figure 6). Normally, therefore, the spring 10 pulls the type carrier 8 away from the platen C and also causes the cross pin 9 to be positioned at the bottom of the slots 11.

For the purpose of manipulating the type carrier 8 by the keys E and F previously referred to, it may be pointed out that the small type key 20 E is a part of the lever 13 pivotally supported on the shaft 14 mounted between the spaced bracket plates 12-12. The forward end or nose 15 of the lever 13 is intended to engage the inside face of the type carrier 8. When the key E is depressed, it will be apparent from an inspection of Figures 3 and 4 that the type carrier will be rocked toward the platen against the tension of the spring 10. When the key E is released, the spring will pull the type wheel 1 and the entire type unit including the carrier 8 back to normal position.

The capital letter key F preferably consists of a key of elongated or bar formation as will be apparent from Figure 1 and is carried by the spaced arms 16 which are bent so as to engage within the inside faces of the bracket plates 12, thereby to receive the pivot shaft 17 also positioned in the spaced bracket walls 12. The arms 16 of the lever beyond the pivot 17 converge as indicated at 18 to eventually meet as indicated at 19 and clamp therebetween a link 20 which is pivotally connected thereto by the pivot element 21 (Figure 3). The upper end of the link 20 is of forked formation to provide the portions 22 and 23, the latter constituting a shoulder adapted to enter a slot 24 in the type wheel carrier 8 so as to provide a point of engagement between the upper end of the link and the type carrier above the pin 9 carried by the latter. 50 When the capital type key F is depressed, the same will be rocked on the shaft 17 thereby forcing the link 20 upwardly which will have the effect of initially lifting the type wheel carrier 8 due to the fact that the cross pin 9 will slide in the slots 11 and elevate the type wheel 1 so as to bring the capital letters 3 in line for printing at the platen. After the initial movement of the type key has effected the lifting of the type wheel, its continued movement will 0 cause the type carrier to rock or tilt toward the platen and thus carry the type wheel with it.

It will, of course, be understood that the spring 10 tensions the type wheel carrier 8 against the operation of both levers 13 and 16-18 so that 55 when finger pressure on either of the keys E or F is relieved, the carrier will be pulled back to normal position and the type wheel will be moved away from the platen. It will also be apparent that the upper portion A' of the casing 70 A constitutes the return abutment or stop means for the upper arm 7 of the type wheel carrier.

Referring now to the platen carriage C, it may be pointed out that the same preferably comprises the front and rear walls 25 and 26 respectively whose lower ends are flanged outwardly to

be guided in the inturned channel portions 27 of a guide member 28 carried by the rear of the casing A. The rear wall 26 may be continued upwardly and bent into substantially arch-shaped formation as indicated at 26^a, and is preferably provided at its rear side with a paper receiving slot 26^b. The front edge is also bent to provide a reinforced channel-like longitudinal platen member receiving seat 26^c. A strip or band of hard rubber or its equivalent 29 is arranged at the front edge of the reinforced seat portion 26^a of the carriage element, thereby to provide a platen surface for receiving type impact imposed on the paper overlying the platen. The ends of the front and rear carriage walls 25 and 26 and the arched top wall 26^a are closed by the cap members 30 and 31 respectively (Figure 1). Within the housing provided by the construction just described, there is provided a paper feeding and guiding member which has a portion 32 projecting outwardly through the slot 26^b to receive and guide the paper into the slot, and also has an interior guiding surface 33 for directing the paper upwardly between the top edge of the front wall 25 and the reinforced seat portion 26^c which carries the platen strip 29. The end walls 30 and 31 of the carriage have journaled therein a shaft 34 which is located within the housing afforded by the rear and top walls of the carriage. This shaft is provided with rollers 35 which are preferably made of rubber and are intended to frictionally grip a paper sheet passing over the guide portions 32 and through the opening 26^b. The portions of the shaft 34 which project beyond the end caps 30 and 31 are respectively provided with operating knobs 36 and 37. The knob 37 is provided with a flanged serrated disk 38 which is intended to cooperate with a resilient lug 39 or its equivalent so that the operator may manipulate the knob, 40 and consequently the rollers 35, step by step to obtain proper line spacing of the typed material.

The front wall 25 of the carriage, which is slidably mounted on the casing as above described, is 45 provided with a series of rack teeth 40 which are intended to be engaged by the platen feeding means D.

As will be observed from Figures 7 and 8, this platen feeding means includes a lever 41 pivotally 50 connected as at 42 with an arm 43 whose forward end projects through the top portion A' of the casing and is provided with a finger grip 44. The lever 43 is pivoted to the bottom side of the casing portion A' as indicated at 45. The lever 41 is urged in one direction by a spring 46 having one end anchored to an offset portion of a lever while the opposite end is anchored as at 47 to one of the bracket plates 12. The lever 41 is further provided with an offset portion having 60 a pair of teeth 48 for normally engaging with adjoining teeth 49 formed on the wall 25. It will be apparent that the spring 46 tensions the lever 41 so that this normal engagement is effected. The lever 41 is provided with an extension 49 adapted to overlie the end 50 of a detent lever 51. This is pivoted in a fixed position by the stud 52 to the underside of the casing A' and has an offset portion 51^a. The detent lever 51 is tensioned by a spring 53, one end of which connects with the lever while the other end is anchored to a perforated ear 54 (Figure 1) of one of the bracket plates 12. The detent lever is provided with a single tooth 55 which also engages with the teeth 48 of the carriage to prevent back- 70 75

ward or retrograde movement of the carriage under normal conditions.

The finger grip 44 of the lever 43 is located adjacent a fixed finger grip element 44^a on the outside of the casing as will be apparent from Figure 1. When the operator grips the parts 44 and 44^a and moves 44 toward 44^a, the lever 43 is moved to the dotted line position shown in Figure 7, and, consequently, the lever 41 is shifted to the left and the platen carriage is moved the desired distance through the medium of the teeth 48 which engage with the toothed rack 40. When the operator releases the grip 44, the spring 46 returns the lever 41 to normal position, and it will, of course, be understood that the detent lever 51 merely idly trails over the teeth 40 when the carriage is advanced, but comes quickly into position to prevent backward movement of the platen carriage.

When it is desired to move the carriage back to starting position, the lever 43 is moved in the opposite direction to that which it is moved to effect carriage feed as will be apparent from Figure 8. That is to say, the operator will move the finger grip 44 to the full line position shown in Figure 8, that is away from 44^a, so that the inner end of the lever 43 having the depending flange portion 43^a will thereby cause the toothed end of the lever 41 to be moved away from the rack 40 and consequently withdraw the teeth 48 from engagement therewith. This movement of the lever 41 also disengages the detent lever 51 from the rack due to the fact that the extension 49 of the lever 41 engages the laterally offset or upstanding abutment 51^a on the lever 51 as clearly shown in Figure 8. Accordingly, it will be apparent that the movement of 43—44 to the extreme left in Figure 8 will simultaneously cause the teeth 48 and 55 respectively of the carriage feeding and detent levers to disengage the rack teeth 40 of the carriage. When this condition prevails, the entire platen carriage may be shifted backwardly in the guide 28 to starting position.

From the foregoing, it will be apparent that the present invention provides a construction which enables the typist to use the fingers of the right hand entirely for printing small or capital letters without using the left hand to raise and lower the type disk to different positions, thus leaving the left hand free for letter spacing, that is, carriage movement. Also, the novel carriage construction provides a simple form of platen and paper feeding means which obviates the necessity of a roller. Moreover, the carriage feed is simple and accurate and insures uniform letter spacing.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:—

1. A toy typewriter including a casing, a platen, a support within the casing having slots, a rotatable type wheel unit having upper and lower rows of type characters, a carrier for the type wheel having means for operating in the slots of the support whereby the carrier may be rocked and also raised and lowered with reference to the platen, separate key levers for actuating the carrier to cause it to tilt, and one of said levers having means for lifting the carrier.

2. In a toy typewriter, spaced frame parts having slots, a rotatable type wheel, a carrier for said type wheel tensioned in one direction by a spring and arranged between said frame parts, offset members on the carrier for engaging in said slots, a lever for rocking said carrier when the offset members are in the bottom of the slots, a second lever having a link for engaging with said carrier to first lift the same until the offset members engage the tops of said slots and then rock the carrier. 5

3. In a toy typewriter, spaced frame parts having slots, a rotatable type wheel, a carrier for said type wheel tensioned in one direction by a spring, said carrier having side flanges and arranged between said frame parts, pin portions projecting laterally from the lower sides of the flanges and normally resting in the bottom of the slots, a lever for slidably engaging the carrier and a second lever having a link connected thereto for engaging the carrier to first lift and then tilt the carrier. 15

4. In a toy typewriter, spaced frame parts having slots, a rotatable type wheel, a carrier for said type wheel tensioned in one direction by a spring and arranged between said frame parts, said carrier being of sheet metal and having side flanges and a medially located vertical slot, pin portions projecting from the lower sides of the flanges and engaging in said frame slots, a lever 20 for slidably engaging with the carrier at opposite sides of the slot therein, a second lever having a link provided with a shoulder normally lying in the slot of the carrier and adapted to engage the upper edge of the slot when the lever 30 is moved to first lift and then tilt the carrier. 35

5. In a toy typewriter, spaced frame parts having slots, a rotatable type wheel having rows of characters thereon, a carrier for said type wheel tensioned in one direction by a spring, said carrier being arranged between said frame parts and including a body having an angularly offset arm supporting the type wheel and having flanges formed at its side edges with a slot in the body between the flanges, offset elements carried by 45 the flanges for engaging in said slots of the frame parts, a lever engaging directly with the body of the carrier for tilting the same, and a second lever including a link adapted to engage directly with the carrier in the said slot of the 50 body thereof, said second lever being adapted to first lift and then tilt the carrier.

6. In a toy typewriter, spaced frame parts, a type wheel carrier spring tensioned in one direction and mounted for sliding movement between 55 said frame parts, and separate key levers for actuating said carrier, one of said levers having a sliding engagement with the carrier and the other having a flexible connection therewith to first lift and then rock the same. 60

7. A toy typewriter including a rotatable type unit having separate rows of small and large type characters, means for manually selecting the characters desired, said means comprising a key lever for small type and a key lever for large 65 type, and a carrier for said type unit mounted for shifting movement and having a slot, said key lever for the small type characters engaging the carrier to actuate the same, and said key lever for the large type characters having a pivoted 70 link for engaging with an edge of said slot in the carrier to shift the same when the last mentioned key lever is moved. 75
